LUGGAGE CARRIER

Filed Aug. 20, 1928

FIG. 1.

Inventor
Herman J. Beauford

Patented May 7, 1929.

1,711,717

UNITED STATES PATENT OFFICE.

HERMAN J. BEAUFORD, OF HIGHLAND PARK, MICHIGAN.

LUGGAGE CARRIER.

Application filed August 20, 1928. Serial No. 300,681.

The present invention pertains to a novel luggage carrier adapted for attachment to the running board of an automobile.

The principal object of the invention is to 5 provide a simple and inexpensive device of this character, which is more in the nature of a bag than a trunk, and which may therefore be folded into a compact parcel when not in use.

10 The carrier or receptacle is made of canvas or other durable fabric and is maintained in service position by means of frame members attached to the running board of the automobile. The bag is held by these frame 15 members so that it may be filled with parcels or whatever articles are to be carried. The uprights are secured to the running board by means of clamps and support a cross bar which determines the length of the luggage 20 carrier. The uprights are readily removable from the running board and are easily disassembled from the cross bar, so that various parts may be rolled into a neat and compact bundle.

25 The invention is fully disclosed by way of example in the following description and in the accompanying drawings in which—

Figure 1 is a perspective view of the device attached to the running board of a 30 motor vehicle;

Fig. 2 is an elevation of the frame;

Fig. 3 is an end view thereof on the line 3—3 of Fig. 2; and

Fig. 4 is a plan view thereof.

35 Reference to these views will now be had by use of like characters which are employed to designate corresponding parts throughout.

In Figure 1 the numeral 1 indicates a running board on which the luggage carrier is 40 to be clamped and supported. Inasmuch as the carrier or receptacle is made of canvas or other fabric which is not necessarily stiff at all times, a supporting frame is necessary.

45 This frame consists of two upright members 2 having their lower ends bent at right angles as indicated by the numeral 3 to be slipped under the running board as illustrated in Fig. 1. Above the bent end 3 a right angular bracket 4 is secured to the uprights by rivets 5 in such a manner as to have a portion 4' parallel to the part 3. The spacing between these parts is such that the running board 1 may conveniently be received therebetween. A clamp screw 6 threaded through the part 3 binds against

the lower surface of the board 1 and draws the portion 4' against the upper surface, whereby the uprights 2 are securely clamped to the board.

60 The receptacle 7 is made of canvas or other similar fabric suitable for the purpose and has a general box-like configuration, tapering towards the upper end to conform to the automobile body, as illustrated in Fig. 1. 65 A cover 8 of like material overlaps the upper edge of the receptacle and is stitched to the latter along its rear upper edge along the line 9. The lateral ends of the cover are formed with flaps 10 which are extended 70 around the back of the receptacle without stitching them so that the cover may readily be raised.

75 In the forward vertical corners of the receptacle are stitched webs 11 forming each a pocket 12. A pair of apertures 13 are formed in the lower corners of the front wall of the receptacle to communicate with the pockets, and similar apertures 14 are formed in the upper corners. Thus, the uprights 2 which have been secured to the running board may enter the pockets through the apertures 13 and pass out of them through the apertures 14, whereby they are almost entirely contained in the pockets 12.

80 An extensible cross bar is provided between the uprights 2 and consists of a pair of sections 15 and 16 having their outer ends respectively pivoted on the uprights 2 by means of pins 17. The inner ends of the 90 sections are overlapped and are received in U-shaped clips 18. Each clip has a threaded stud 19 passed through its ends and a wing nut 20 mounted on the stud, whereby the clips may bind the sections 15 and 16 together in any desired adjustment. A pin 21 held frictionally in the section 15 adjacent one of the clips 18 further prevents slipping.

95 The cross bar is secured to the uprights at the exposed ends thereof outside of the pockets 12. These ends and the cross bar therefore lie outside of the receptacle 7 but are in turn concealed by the cover 8 as clearly shown in Fig. 1. Straps 22 hang 100 from the cover and are received in buckles 23 secured on the receptacle.

105 It will be apparent that the framing structure maintains the position of the front wall of the receptacle, although the back part thereof may sag due to the pliable nature of the material. The receptacle may how-

ever be filled with parcels or other articles to be carried and will assume the appearance of a bag rather than a trunk.

Although specific embodiments of the present invention have been illustrated and described, it will be apparent that various alterations in the details of construction may be made without departing from the scope of the invention as indicated by the appended claims.

What I claim is—

1. A luggage carrier comprising a pair of upright frame members adapted for attachment to the running board of a motor vehicle, and a bag member having corner pockets adapted to receive said uprights.

2. A luggage carrier comprising a pair of upright frame members adapted for attachment to the running board of a motor vehicle, and a bag member having corner pockets adapted to receive said uprights, and a cross bar extending across said uprights.

3. A luggage carrier comprising a pair of upright frame members adapted for attachment to the running board of a motor vehicle, and a bag member having corner

pockets adapted to receive said uprights, said bag member having lower apertures through which said uprights enter said pocket, and having upper apertures through which said uprights pass from the pocket to the outer surface of the bag member, and a cover laid over said bag member and concealing the upper ends of said uprights.

4. A luggage carrier comprising a pair of upright frame members adapted for attachment to the running board of a motor vehicle, a fabric bag member held by said members, and a cross bar connected across the upper ends of said members, exteriorly of the bag.

5. A luggage carrier comprising a pair of upright frame members adapted for attachment to the running board of a motor vehicle, a fabric bag member held by said members, and a cross bar connected across the upper ends of said members, exteriorly of the bag, and a cover laid over said bag and concealing the upper ends of said members and said cross bar.

In testimony whereof I affix my signature.

HERMAN J. BEAUFORD.
